DESIGN FOR A JAR

Frank McIntosh, New York, N. Y., assignor to Lentheric Incorporated, New York, N. Y., a corporation of New York

Application March 2, 1938, Serial No. 75,529

Term of patent 7 years

To all whom it may concern:

Be it known that I, Frank McIntosh, a citizen of the United States, residing at New York city, in the county of New York and State of New York, have invented a new, original, and ornamental Design for a Jar, of which the following is a specification, reference being had to the accompanying drawing, forming part thereof.

In the drawing:

Fig. 1 is a top view of a jar embodying my design; and

Fig. 2 is a front view thereof.

I claim:

The ornamental design for a jar, substantially as shown.

FRANK McINTOSH.
